Attest:

UNITED STATES PATENT OFFICE.

GEORGE H. DAWSON, OF BOSTON, MASSACHUSETTS, ASSIGNOR TO SERVICE BUREAU, INC., OF CAMBRIDGE, MASSACHUSETTS, A CORPORATION OF MASSACHUSETTS.

REINFORCED INDEX CARD.

Application filed January 27, 1928. Serial No. 249,993.

This invention relates to guide cards provided with projection tabs, such as are commonly employed in a vertical filing system to separate into indexed groups the card, 5 folders or other index material constituting the filing system. The principal object of the invention is to provide an improved metal reenforcement for the guide card, so constructed and arranged that the card and 10 its tab are adequately strengthened and protected against bending stresses and destructive handling without, however, the formation of a straight line at the bottom of the reenforcing member upon which the card 15 might tend to fold and crack.

A preferred embodiment of the invention is illustrated in the accompanying drawings, in which:

Fig. 1 is a face view of a guide card 20 equipped with the improved reenforcement;

Fig. 2 is a rear view thereof; and

Fig. 3 is an enlarged section on the line 3—3 of Fig. 1.

The card body 4 and its integral projecting tab 5 may be made of any suitably stiff sheet material, such as cardboard, fiber board or the like, and may be of any desired size or shape. The tab is adapted to display index characters which may be inscribed directly upon the face of the tab or may appear upon a separate slip which is pasted or otherwise attached to the tab, in order to 30 identify the subject matter behind the particular guide card.

The front face of the tab and the index characters may be protected from moisture and soilage by an adhesively secured strip 6 of transparent material, such as celluloid, or by a coating of collodion, shellac or other 40 transparent and hard-drying fluid. The sheet material or coating constituting the protective covering preferably covers the surface of the tab and has its lower edge 7 extending parallel with and adjacent to the 45 upper edge 8 of the card body.

A metal reenforcing plate 9 is applied flatwise upon the rear face of the card and tab and is preferably secured at its upper edge by means of a top flange 10 which is rolled or 50 crimped over the top and shoulders of the card tab and over the protective covering.

The bottom of the plate 9 may be fastened to the card body by eyelets 11, or other suitable means. In order to avoid the formation of a predetermined line of fold at the bottom of the plate, upon which the card might bend or crack during handling, the bottom margin of the plate is centrally recessed at 12 and the bottom corners 13 are preferably rounded to provide a curvilinear 60 edge.

It will be noted that the rolled flange 10 completely encloses the top edges and shoulders of the card tab 5 and celluloid covering 6, and extends downwardly to hold the bottom corners of the celluloid tightly against the card surface. The bottom edge 7 of the celluloid is accordingly secured flatwise against the card so that it will not be separated therefrom by accidental contacts, 70 and whereby it prevents papers or other objects from catching under said edge.

I claim:

1. An index card having an integral projecting tab provided on its front face with a protective covering of transparent material, and having a reenforcing plate applied to the rear face of the card and tab, said plate having a top flange rolled over the upper edge and shoulders of the tab and its covering, and fasteners near the bottom corners of the plate, the bottom margin of the plate having a deep, curved, central recess to avoid a predetermined line of fold.

2. An index card having an integral projecting tab provided on its front face with a protective covering of transparent sheet material, and having a reenforcing plate applied to the rear face of the card and tab, said plate having a top flange rolled over the upper edge and shoulders of the tab and its covering, and fasteners near the bottom corners of the plate, the bottom margin of the plate having a deep, curved, central recess to avoid a predetermined line of fold.

3. An index guide comprising a card having an integral tab projecting above its upper margin adapted to display index characters, a protective covering of transparent sheet material applied on the front face of the tab, said covering having its upper edge and shoulders substantially coinciding with

the top edge and shoulders of the card tab and having its bottom edge terminating adjacent and parallel to the said upper margin of the card, and a reenforcing plate secured 5 flatwise upon the rear surface of the card and tab, said plate having a top flange rolled over the upper edge and shoulders of the

card tab and its covering, the ends of said flange enclosing the bottom corners of said protective covering.

10

Signed by me at Boston, Massachusetts, this twenty-third day of January, 1928.

GEORGE H. DAWSON.
